UNITED STATES PATENT OFFICE

HOWARD M. LEONARD, OF SOUTH BEND, INDIANA, ASSIGNOR TO GERNANDT MOTOR CORPORATION, OF CHICAGO, ILLINOIS, A CORPORATION OF ILLINOIS

ENGINE

Application filed April 2, 1927, Serial No. 180,504. Renewed October 2, 1930.

This invention relates to engines, and is illustrated as embodied in a two-cycle Diesel engine of the double-diameter piston type. An object of the invention is to simplify the 5 fuel-injecting mechanism, by arranging the fuel-injecting plunger or its equivalent for direct operation by the engine piston. In one desirable arrangement, the plunger is in a relatively small cylinder beside and parallel 10 ing the smaller-diameter portion of the engine cylinder, and is operated by direct engagement with the larger-diameter part of the engine piston.

The above and other objects and features 15 of the invention, including various novel arrangements and desirable particular constructions, will be apparent from the following description of one illustrative embodiment shown in the accompanying drawing, in 20 which:

The figure is an axial section through the engine cylinder and piston, and through the fuel-feeding mechanism, of a two-cycle Diesel engine.

25 The illustrated engine includes a cylinder block 10, having the usual passages 12 for water cooling, and providing at its upper end a smaller-diameter portion for the corresponding part 14 of the engine piston. The 30 cylinder block also has a larger-diameter portion, shown as formed in a separate casting 16, for the larger-diameter part 18 of the engine piston. A detachable cylinder-head 20 is shown secured to the block in any desired manner.

35 Beside and paralleling the smaller-diameter portion of the engine cylinder, and intersecting the larger-diameter portion adjacent its periphery, the cylinder block is formed 40 with a pump cylinder 22, which may be closed by means such as a threaded plug 24 at its upper end. The fuel is introduced into the pump cylinder in any desired manner, e. g. through a conduit 26, and is there mixed with 45 and vaporized in a charge of air or exhaust gas. The mixture is then compressed by a pump plunger 28 in the pump cylinder, and at the end of the compression stroke of the piston 14 it is injected into the engine cylinder, 50 through a passage 30 through the plunger,

which at that instant registers with a passage 32 through the cylinder wall.

The pump plunger may be formed with a separate and readily-renewable upper portion 34, held in place by a spring 36. According to an important feature of the invention, the plunger is operated directly by the piston 14-18, preferably being connected to the part 18 of the piston by a ball-and-socket joint 40.

55 As the operation of a two-cycle double-diameter-piston engine is well known, extended explanation of the operation of the engine is omitted. The plunger 28, in the arrangement shown, on its downward stroke receives a charge of fuel through conduit 26, and at the lower end of its stroke which is limited by the abutting shoulders 42 and 44 it clears the passage 32, just before the end of the power stroke of piston 14. Hot burned or 60 exhaust gases from the engine cylinder thereupon rush through passage 32 and fill the pump cylinder 22, vaporizing the fuel during the upward stroke of the plunger 28. At the 65 end of this stroke, the vaporized mixture is injected into the engine cylinder through passage 32, the fuel mixture and the air in the engine cylinder both being at such a temperature that the fuel ignites spontaneously, as is usual in Diesel-type engines.

70 While one illustrative engine has been described in detail, it is not my intention to limit the scope of the invention to that particular engine, or otherwise than by the terms of the appended claims.

I claim:

75 1. An engine comprising, in combination, an engine cylinder and a double-diameter piston, and means for feeding fuel to the cylinder including a plunger operated by direct engagement with the larger-diameter portion of the piston, said plunger disconnectedly engaging said larger diameter portion through the intermediary of a ball and 80 socket joint.

85 2. An internal combustion engine having, in combination with a combustion chamber, a compression chamber located at one side thereof, a piston in the combustion chamber, a plunger in the compression chamber, said 90

plunger seated at its lower end within a socket formed in the piston to be actuated by the piston to compress the fuel in the compression chamber.

5 3. An engine comprising in combination, a combustion chamber, a fuel compression chamber located at one side of the combustion chamber and communicating therewith through a fuel passageway, a piston in the combustion chamber, a plunger in the compression chamber adapted to compress the fuel therein and controlling the passageway leading therefrom to the combustion chamber, said plunger being adapted to be actuated directly by the piston.

10 4. An engine comprising a cylinder having concentric bores of different diameter, a relatively small fuel pump cylinder beside and paralleling the smaller diameter cylinder and intersecting the larger diameter cylinder, a step piston within said concentric cylinders, a fuel plunger within said pump cylinder, means urging said plunger downwardly, a stop for limiting downward movement of the plunger, and a stem on said plunger adapted to contact with the step of said piston and be actuated thereby for forcing fuel into the cylinder.

15 5. An engine comprising a cylinder having concentric bores of different diameter, a relatively small fuel pump cylinder, a step piston within said concentric cylinders, a fuel plunger within said pump cylinder, means urging said plunger downwardly, a stop for limiting downward movement of the plunger, and a stem on said plunger adapted to contact with the step of said piston near the top stroke thereof and be actuated thereby.

20 6. An engine comprising a cylinder, a piston having a radial extension, a fuel pump cylinder, a plunger within said pump cylinder, means limiting the downward movement of the plunger and means operatively connected to the plunger adapted to contact with the extension during an end portion of the piston stroke.

25 7. An engine comprising, in combination, a block including a cylinder having a smaller-diameter portion and a larger-diameter portion in axial alignment with each other and having a relatively small pump cylinder beside and paralleling the smaller-diameter portion and intersecting the larger-diameter portion adjacent its periphery, a piston having smaller-diameter and larger-diameter parts in said portions of the cylinder respectively, and a fuel-feeding plunger in said pump cylinder having a limited stroke and operated by said larger-diameter part of the piston.

30 8. An internal combustion engine having a combustion chamber and a fuel compression chamber communicating therewith through a fuel port, a working piston in the combustion chamber, and a working plunger in the

compression chamber adapted to contact with the piston during a portion only of the piston stroke to be reciprocated thereby, and formed with a fuel passageway adapted at one position of the plunger to register with the fuel passageway leading into the combustion chamber.

35 9. An internal combustion engine having, in combination with a combustion chamber, a compression chamber arranged alongside of the combustion chamber and communicating therewith through a fuel port, a piston in the combustion chamber, and a plunger in the compression chamber adapted to be directly engaged by the piston during a portion only of the piston stroke to be actuated thereby to compress the fuel within the compression chamber, said plunger being adapted to control the fuel port leading from the compression chamber to the combustion chamber.

40 In testimony whereof, I have hereunto signed my name.

HOWARD M. LEONARD.
